UNITED STATES PATENT OFFICE.

WILLIAM A. JAMES, OF MILWAUKEE, WISCONSIN, ASSIGNOR OF ONE-HALF
TO THE WILKIN MANUFACTURING COMPANY, OF SAME PLACE.

MOLDER'S FLASK.

SPECIFICATION forming part of Letters Patent No. 443,704, dated December 30, 1890.

Application filed November 17, 1890. Serial No. 371,656. (No model.)

To all whom it may concern:

Be it known that I, WILLIAM A. JAMES, of Milwaukee, in the county of Milwaukee, and in the State of Wisconsin, have invented certain new and useful Improvements in Molders' Flasks; and I do hereby declare that the following is a full, clear, and exact description thereof.

My invention relates to appliances for forming metal castings; and my invention consists in certain peculiar and novel features of construction and arrangement, as hereinafter described, and pointed out in the appended claims.

15 In the drawings, Figure 1 is a plan view of a molder's flask constructed in accordance with my invention. Fig. 2 is an irregular horizontal section of the same on the line 2 2 of Fig. 1. Fig. 3 is a detached perspective 20 view of one of the flask-sections. Fig. 4 is a plan view showing a modified arrangement of the flask-sections.

The objects of my invention are to produce a sectional form of flask the walls of which 25 can be readily varied in shape to accord with variations in the form of the casting to be produced, and at the same time shall possess an equal degree of strength and rigidity to that possessed by the ordinary forms of molders' flasks. These results I attain by virtue 30 of the construction which I will now proceed to describe.

Referring to the drawings, A A designate 35 a number of flat rectangular flask-sections, each of which is formed at one end with a continuous elongated vertical socket a , the outerside of which is formed with a continuous longitudinal opening a' , which lies opposite the point of juncture of the socket with the 40 body of the section, and the axis of which is slightly inclined to the axis of the body A. At its opposite end each of these sections is formed with a continuous vertical elongated head a^2 , the external contour of which corresponds to the internal contour of the socket a and both sockets and heads extending the 45 full height of the sections A. At its inner portion, near one end thereof, each socket is formed with a transverse opening a^3 , while 50 the outer portion of each head a^2 is formed near one of its ends with a transverse recess

a^4 , which when the sections are properly connected registers with the opening a^3 in the adjacent socket a . When the parts are thus assembled, keys b are inserted into the openings a^3 and extend through the recesses a^4 , and thus rigidly connect the two adjacent sections A. It is obvious that in connecting these sections together the heads a^3 are inserted from above or below into the sockets a , so as to bring the openings a^3 and recesses a^4 into alignment with each other, as just described; and it will be seen that by this means the flask-walls can be continued to any desired length, and that the walls thus constructed are as close and rigid as though composed of only a single piece. Furthermore, it will be seen that such walls may be either of straight form, as shown in Figs. 1 and 2, or of a curved outline, as shown in Fig. 4.

When the walls of the flask are set at an angle with each other, as shown in Fig. 1, at one end of each wall is connected a section C, which corresponds in all respects with the sections A, excepting that its socket c is formed with an opening c' , the axis of which is oblique to the body portion of the section, the keys b being used as before.

It is frequently desirable to make a number of separate castings in the same flask, and in such event one or more pairs of sections D are placed opposite each other in the walls of the flask, and these sections D correspond with the previously-described sections A, excepting that on one side and preferably 80 midway of its length each section D is formed with a continuous vertical head d , connected to the body of the section by a rib d' or with a continuous vertical socket d^2 , the axis of whose opening is oblique to the section D. 85 In this event one or more intermediate walls are located in the flask, the said intermediate walls being each composed of a number of sections A, with the sockets a and heads a^2 of their end sections engaging the heads d and sockets d^2 , just referred to. Obviously 90 two or more of these walls may be placed one above the other, so as to form a cope and drag, and in any event a strong, rigid, and durable structure is provided, as above pointed out.

Having thus described my invention, what

I claim as new, and desire to secure by Letters Patent, is—

1. A molder's flask comprising a number of sections having each a continuous elongated vertical head and a continuous vertical elongated open socket, substantially as set forth.
2. In a molder's flask, a number of sections having each a continuous elongated vertical head provided with a transverse recess, and a continuous vertical elongated open socket having a transverse opening, in combination with keys set into said openings and recesses, substantially as set forth.
3. A molder's flask comprising a number of

sections having continuous elongated vertical heads and continuous vertical elongated open sockets at their opposite ends, in combination with interposed sections provided with intermediate heads and sockets, substantially as set forth.

In testimony that I claim the foregoing I have hereunto set my hand, at Milwaukee, in the county of Milwaukee and State of Wisconsin, in the presence of two witnesses.

WILLIAM A. JAMES.
